CLAIM

The ornamental design for a set of cocktail smokers as shown and described.

DESCRIPTION

FIG. 1 is a top perspective view of a first cocktail smoker of a set of cocktail smokers showing my new design, shown separately for ease of illustration;

FIG. 2 is bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top perspective view of a second cocktail smoker of the set of cocktail smokers shown separately for ease of illustration;

FIG. 10 is bottom perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the set of cocktail smokers. The broken lines and the area within the broken lines form no part of the claimed design.
